UNITED STATES PATENT OFFICE

ERNEST A. ARNDT, OF SIOUX CITY, IOWA, ASSIGNOR TO THE GABRIEL KARI-KEEN COMPANY, OF SIOUX CITY, IOWA, A CORPORATION OF DELAWARE

HINGE

Application filed April 14, 1930. Serial No. 444,021.

My invention relates to the hinge and has for its object to provide a hinge that is particularly adapted to be used for connecting the members of a sheet metal trunk or the like.

More particularly it is my object to provide a hinge of exceedingly sturdy construction and yet simple and inexpensive to produce.

10 A further object is to provide a hinge in combination with the walls of a receptacle such as a sheet metal trunk which can be easily and quickly assembled.

Another object is to provide a hinge structure in combination with the walls of a receptacle, the hinge structure being adapted to exclude to a large extent dust and moisture from the interior of the receptacle.

15 A further object is to provide a hinge which is particularly adapted to support the strain imparted to the horizontal wall, the movable member of a combination trunk and luggage carrier when loaded.

20 A further object is to provide a hinge which is pleasing to the eye in addition to being strong, simple and otherwise advantageous as above noted.

25 With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Fig. 1 is a plan view of a combination trunk and luggage carrier embodying the hinge construction of my invention.

Fig. 2 is a plan view of the hinge enlarged.

40 Fig. 3 is a detail, sectional view taken on the line 3—3 of Fig. 1.

Fig. 4 is a detail, sectional view taken on the line 4—4 of Fig. 1.

45 Fig. 5 is a detail, sectional view similar to Fig. 3 with the trunk members in relatively closed positions.

The type of trunk for which my hinge has been primarily intended is that wherein a fixed trunk member A of sheet metal is rigidly supported on the rear of a vehicle and a

movable trunk member B, also of sheet metal, is hinged to the fixed trunk member A for swinging movement from a position wherein it forms together with the fixed trunk member A a closed trunk to a position wherein it cooperates with a fixed trunk member A to form an open top luggage carrier as shown in Fig. 1.

The walls of the respective members A and B which form the bottom of the open luggage carrier are indicated by the reference characters 10 and 11, respectively. These walls are hinged together. The side walls 12 and 13 of the fixed and movable trunk members, respectively, are provided with coacting devices 14, which limit the outward swinging movement of the movable trunk member to a substantially horizontal position. These coacting members support the weight of the luggage carried by the luggage carrier.

It will now be seen that the function of the hinge between the walls 10 and 11 are several, as follows: to support the adjacent region of the wall 11 against the load pulling directly downward thereon; to receive an end thrust of the wall 11 caused by the weight of the luggage in the movable member B pulling downwardly against the outer extremity of the member B and tending to swing it about an axis defined by the engagement of the elements 14 near the upper ends of the walls 12 and 13; to form a weather-tight connection between the walls 10 and 11 when the trunk is open; and to allow hinging movement of the member B to an upright standing position at right angles to the one shown in Fig. 1.

The wall 11 is provided with a plurality of spaced slots 15 which form between them a plurality of spaced tongues 16 (see Fig. 3). The tongues 16 are bent back beneath the wall 10 to form a plurality of hinge sleeves 17.

The metal of the wall 10 adjacent the slots 15 is pressed upwardly to form a series of hoods 18, which are connected to the sleeves 17 as at 19 by the corner portions of extruded metal. It may now be noted that the slots 15 extend only part way through the hinge 100

sleeves 17, the hoods 18 forming enlarged continuations of the sleeves.

The bottom wall 11 of the member B is provided with a series of hinge hooks 20, which substantially fill the slots 15 from side to side and which are riveted or welded to the wall 11 as at 21. The hooks 20 are provided with flat shanks 22, which are received between the wall 11 and a false bottom 23 and spot welded or riveted therebetween. The hook portion of each hook 20 terminates in an end portion 24, which is perpendicular to the plane of the shank 22 and terminates in the plane of the lower face thereof. The terminal portions 24 of the hooks thus will rest in flat contact with the bottom wall 11, as shown in Fig. 3.

The wall 11 serves to close the open side of the hook to form a hinge loop. A reinforcing band 25 extends from side to side of the movable trunk member B and its riveted or spot welded to the lower face of the wall 11 by the same means which secures the hinge loops in place.

It may now be noted that the wall 11 extends beneath the inner extremities of the slots 15, a serving in conjunction with the hooks 20 to close the slots from below. The extended portion of the wall 11 will contact snugly with the underturned tongues 16 between the slots 15 to tightly close the regions between the slots. The hooks 20 engaging both the wall 11 and the hoods 18 as shown in Fig. 3 and substantially filling the slots 15 from side to side serve to close the spaces formed by the slots 15 between the wall 11 and the hoods 18.

A hinge pin 30 extends through the hinge loops 17 and hooks 20 and completes the hinge.

In assembling the trunk, the hooks 20 may be inserted between the walls 11 and 23 and held there by friction while the member B is fitted to the member A and then adjusted to the exact positions necessary to register snugly in the slots 15. A hinge pin may then be inserted and the welding or riveting accomplished with the hinge assembled. The process is very simple and eliminates error.

Downward pressure on the bottom 11 will be transmitted through the rigidly associated hooks 20 to the hinge pin 30. In this connection, it will be noted that the hook 20 opens downwardly and downward pressure will be transmitted from the crown portions of the hooks to the hinge pin.

End pressure of the wall 11 will be transmitted through the hooks 20 to the hoods 18, with which they are in contact.

Since the hinge loops formed by the hinge 20 are displaced upwardly from the bottom of the member B, the latter will be allowed to fold upwardly to a vertical position as shown in Fig. 5, in which position the wall 23 will closely approach the edges of the hoods 18.

It will be understood that the hinge construction of my invention may be applied to other constructions than the particular type of trunk or receptacle shown herewith. The main advantages of the invention are found, however, in a construction where strength, simplicity and weather-tight qualities are required.

Some changes may be made in the construction and arrangement of the parts of my invention without departing from the real spirit and purpose of my invention, and it is my intention to cover by my claims any modified forms of structure or use of mechanical equivalents, which may be reasonably included within their scope.

I claim as my invention:

1. In a hinge, in combination with a pair of sheet metal walls to be hinged together at their edges, hinge loops formed in the metal of one of said walls and spaced by a slot cut in said metal, a hinge pin extended through said loops, the other wall when in one position being adapted to overlap the wall having the hinge loops, and a hinge element secured to the second mentioned wall and provided with an open sided hook extended over the hinge pin, received in the slot, and closed by the overlapping portion of the second mentioned wall.

2. In a hinge, in combination with a pair of sheet metal walls to be hinged together at their edges, hinge loops formed in the metal adjoining the edge of one of said walls and spaced by a slot cut in said metal, the metal surrounding said slot being extruded upwardly to form a curved hood merging at its ends with said hinge loops, a hinge pin extending through the loops, and a hinge element on the other wall, received in said slot, receiving the pin, and in engagement with the inner curved sides of said hoods.

3. In a hinge, in combination with a pair of sheet metal walls to be hinged together at their edges, hinge loops formed in the metal adjoining the edge of one of said walls and spaced by a slot cut in said metal, the metal surrounding said slot being extruded upwardly to form a curved hood merging at its ends with said hinge loops, a hinge pin extending through the loops, the other wall when in one position being adapted to overlap the wall having the hinge loops and a hinge element secured to the second mentioned wall and provided with an open sided hook extended over the hinge pin received in the slot and closed by the overlapping portion of the second mentioned wall.

4. In a hinge, in combination with a pair of sheet metal walls to be hinged together at their edges, hinge loops formed in the metal adjoining the edge of one of said walls and spaced by a slot cut in said metal, the metal surrounding said slot being extruded upwardly to form a curved hood, a hinge pin

extending through the loops, the other wall when in one position being adapted to overlap the wall having the hinge loops and a hinge element secured to the second mentioned wall and provided with an open sided hook extended over the hinge pin received in the slot and closed by the overlapping portion of the second mentioned wall.

5. In a hinge, in combination with a pair of sheet metal walls positioned in overlapping relation, hinge loops formed in the edge of one of the walls, providing a slot, a hinge pin extending through the loops, and a hinge element comprising a flat bar portion secured to the other wall, said bar portion terminating in an open sided hook extending over the hinge pin closed by the metal of said last mentioned wall and received in the slot.

6. In a hinge, in combination with a pair of sheet metal walls positioned in overlapping relation, hinge loops formed in the edge of one of the walls, providing a slot, a hinge pin extending through the loops, and a hinge element secured to the other wall and provided with an open sided hook extending over the hinge pin, closed by the metal of said last mentioned wall, and received in the slot, the metal surrounding said slot being extruded upwardly to form a curved hood in close proximity to the outer surface of said hook whereby the latter is snugly received within the hood.

7. In a receptacle construction, a pair of sheet metal walls positioned in overlapping relation, hinge loops formed in the edge of one of the walls providing a slot, a hinge pin extending through the loops, a lining wall mounted in spaced relation to the other wall and a hinge element comprising a flat portion secured between the lining wall and said other wall and terminating in an open sided hook receiving the hinge pin closed by the metal of said other wall and received in the slot, the metal adjoining said slot being extruded upwardly to form a curved hood, the outer surface of the hood being in close proximity to the inner surface of the hood to form a weather shell.

8. In a receptacle construction, a pair of sheet metal walls positioned in overlapping relation, hinge loops formed in the edge of one of the walls providing a slot, a hinge pin extending through the loops, a lining wall mounted in spaced relation to the other wall, and a hinge element comprising a flat portion secured between the lining wall and said wall, the said flat portion being rigidly secured to both of said walls, and a flat bar portion secured to the other wall to provide rigid supporting means for said flat portion and said flat portion terminating in an open sided hook receiving the hinge pin closed by the metal of said wall and received in the slot, the metal adjoining said slot being extruded upwardly to form a hood, the outer

surface of the hook being in close proximity to the inner surface of the hood to form a shell.

Signed this 25th day of March, 1930, in the county of Woodbury and State of Iowa.

ERNEST A. ARNDT.
